THERMOPUMP SYSTEM

Haswell E. Staehle, Columbus, and John K. Siddle, Canal Winchester, Ohio, assignors, by mesne assignments, to Midland-Ross Corporation, Cleveland, Ohio, a corporation of Ohio

Filed Feb. 21, 1958, Ser. No. 716,636
14 Claims. (Cl. 103—255)

This invention relates to a thermopump system which is particularly adapted to deliver a continuous flow of liquid being pumped, and to do so at higher pressures and better efficiency than heretofore known with thermopumps.

The commercial application of thermopumps has been suffering for many years from limitations of efficiency and liquid delivery pressure. While the basic principles of a thermopump were shown in U.S. patent to Thayer 47,051 issued in 1865, continual improvement through U.S. patent to Kleen 2,757,618 still attempts to improve cyclic flow apparatus while contending with the loss of effective use of steam at the start and end of each cycle, during which the apparatus shifts from a liquid delivery phase to a liquid recovery (condensation) phase, and vice-versa.

In known thermopumps, as the steam expansion cycle reaches completion and steam escapes, as through a steam trap, to a condensation chamber, pressure in the steam generating or vaporizing chamber drops, causing a flash generation of steam from the vaporizing chamber. Also, there is usually a continuing application of heat to the vaporizing liquid during this condensing cycle. These factors produce steam (or vapor), called "parasitic steam" herein, which is not usefully employed in the pumping cycle to pump liquid, and in fact contributes greatly to the non-functioning referred to in Patent 2,757,618 above noted because it must be condensed and may require more cool water than is available for the purpose.

This invention applies to a thermopump system a single, continuous vapor generator in conjunction with a plurality of pumping and condensing systems in a manner to substantially eliminate the undesirable effects of parasitic steam and enabling a thermopump system to efficiently and continuously pump a liquid against higher pressures than prior art systems. The preferred form of the apparatus embodying this thermopump system so effectively organizes the relative positions and functions of the elements thereof that considerably more effective use of space results, contributing greatly to the effective use of the apparatus in vehicles where space, weight or efficiency is at a premium.

For a further consideration of what we believe to be novel and our invention attention is directed to the following portion of the specification, and the drawings and concluded claims thereof.

FIGURE 1 is a sectional view of preferred apparatus according to this invention.

FIGURE 2 is a schematic diagram of simplified apparatus according to the invention.

FIGURE 3 is a sectional view of FIGURE 1 taken through line 3—3.

FIGURE 4 is a sectional view of FIGURE 1 taken through line 4—4.

FIGURE 5 is a bottom view of the apparatus of FIGURE 1.

The schematic diagram of FIGURE 2 illustrates thermopump apparatus having a vapor generating chamber 11 supplied with heat by a heating coil 12, pumping chambers 13 and 14 interconnected to the chamber 11 by upper ducts 15 and 16 and by lower ducts 17 and 18, and condensing chambers 21 and 22 interconnected to the pumping chambers by lower ducts 23 and 24 and U-shaped upper (steam trap) small ducts 25 and 26.

2

In the operation of FIGURE 2 apparatus, liquid, in this case generally referred to as water (although other liquids such as water-glycol or water-alcohol mixtures may commonly be used), in the vaporizing chamber is continuously subjected to heat from a heating coil and delivers steam (or vapor) to a reversing ball valve 27 whose ball 28 is shown at the left after a pumping cycle in pumping chamber 13. This pumping cycle has just ended with the escape of steam around the trap in the small duct 25, and up into the condensing chamber 21.

As the steam from the duct 25 condenses, the pressure in the chamber 21 drops rapidly from the operational delivery pressure, which in this improved apparatus may be easily 20 p.s.i.g., to the pressure corresponding to the vapor pressure of the vapor liquid system at the temperature of the cooling liquid in the condensing chamber after the condensing cycle. This reduction of pressure closes a check valve 31 in an outlet, or delivery, duct 32 from the condensing chamber, and it moves the ball 28 in the reversing ball valve 27 to the left to snap the duct 15 closed and start delivery of steam to the other duct 16 leading to pumping chamber 14, preventing liquid from entering the vaporizing chamber during the condensing cycle by continuous supply of steam therefrom to the valve 27. A check valve 33 in duct 17 is also held closed by the drop in pressure in the chamber 13 and the loss of the volume of steam in the pumping chamber 13 is replaced by an inflow of water from a return duct 34 through a check valve 35 therein, and through the condensing chamber 21 and the lower duct 23. Since the chambers 21 and 13 are now sealed from the chamber 11, they are not subject to continued heating from parasitic steam, and the volume of cooling water space in the condensing chamber 21 may accordingly be quite small in comparison to prior practice.

Steam from the generating chamber 11 passes through upper duct 16 to pumping chamber 14 and builds pressure therein rapidly to the system delivery pressure, and water is displaced through duct 24 and condensing chamber 22, and through a check valve 36 into the delivery duct 32. To avoid loss of efficiency, an insulating float 37 in the pumping chamber is used to reduce the cooling and condensing of steam in the pumping chamber. The pressure in this pumping cycle is contained by check valve 33 in duct 17 and check valve 42 in return duct 34. As the water level in pumping chamber 14 starts to fall, water is delivered through valve 36 to the delivery duct 32. To accommodate changes in total volume of the system an expansion chamber 43 is inserted, preferably in the delivery duct 32 as shown. Water from the delivery duct, warmed by the condensing cycle, is delivered to the desired apparatus 44, which may be the cooling system of a vehicle engine, and is returned by the duct 34. As the liquid level in pumping chamber 14 drops to the bottom of the trap in duct 26, the steam escapes to the condensing chamber 22 and the cycle reverses as before. The supply of water to be vaporized in the chamber 11 is replaced at the start of the pumping cycle by the hydrostatic U-tube effect, the static head in the pumping chamber 13 now full with its float 38 at the top, driving liquid through check valve 33 and duct 17 into chamber 11.

Since the volume of liquid required to generate the steam for each pumping cycle is small the volume of liquid in the chamber 11 is kept at a minimum for the purpose.

The foregoing describes the continuous flow thermopump system in principle, and its preferred embodiment into physical apparatus will now be described in connection with a unit designed for extremely compact space requirements on vehicles for standby operation, to keep

engines and batteries warm for instant starting operation.

FIGURE 1, together with FIGURES 3, 4, and 5 show a continuous flow thermopump designed to additionally heat the liquid being pumped, and it accordingly contains a specially designed combustion and liquid heating system.

In FIGURE 1 the apparatus is designed in a generally vertical cylindrical shape, divided by separable gasketed flange joints 51 and 52 into an upper, condensing section, an intermediate, liquid heating section, and a lower, pumping section. This design makes possible combinations of various sizes of components for various uses, some of which may, for example, require more heat input in the liquid heating center section than others.

To simplify the understanding of FIGURE 1 apparatus, the essential chambers and functional parts corresponding to those described in FIGURE 2 are given corresponding numbers. Hence in the top, or condensing section, there is a condenser 22 having an inlet, check valve 42, and the outlet check valve 36 is, for reasons to presently appear, shown at the bottom of the apparatus. A second condensing chamber 21, with its inlet check valve 35, is shown at the top, and its outlet check valve 31 is at the bottom of the pumping section opposite the other valve 36. As shown more clearly in FIGURE 3, but with lines for water omitted for clarity, chambers 22 and 21 are divided by a common wall 60.

Below the lower flanged joint 52, the vaporizing chamber 11 is formed by concentric cylindrical walls 53, 54, the inner wall 53 also forming combustion chamber 90 for burning fuel in a burner 57 schematically shown. The fuel supplied by pipe 58, FIGS. 3, 4, and 5 will ordinarily be the vehicle fuel, such as gasoline. Surrounding the vaporizing chamber 11 are the pumping chambers 14 and 13 divided by a common wall 61 more clearly shown in FIGURE 4. The floats 37 and 38 are shown in positions corresponding to those in FIGURE 2. Pumping chamber 14 is interconnected to the vaporizing chamber 11 by upper duct 16 and reversing ball valve 27 and by lower duct 18 and ball check valve 41 therein. The pumping chamber 14 is connected to the condensing chamber 22 by a steam trap duct 26 which discharges through a distribution ring or manifold 62 having ports 63 therein.

Pumping chamber 13 is interconnected to the vaporizing chamber 11 by upper duct 15 and reversing ball valve 27 (and duct 64 with an orifice outlet 67) and by lower duct 17 and ball check valve 33 therein. The pumping chamber 13 is connected to the condensing chamber 21 by a steam trap duct 25 which discharges through a distribution ring or manifold 66 having ports 65 therein.

The apparatus of FIGURES 1, 3, 4, and 5 is started by delivering fuel to the burner 57 and igniting the same, as by spark ignition or torch. Air for combustion enters the bottom of the combustion chamber 90, initially from the end of the last prior operation and subsequently by action of a fan impeller 71. Part of the air for combustion is delivered between the bottom closure 56 for the vaporizing chamber 11 and the fan impeller 71, but mostly it is delivered upwardly between the outer wall 54 and a cylindrical wall 72 which is joined to the top closure 55 of the vapor generating chamber 11 to form an air supply chamber. Tubes 73 extending between walls 53 and 54 pass combustion air from the air supply chamber, through the vapor generating chamber 11 and into the combustion chamber 90 where it burns with the fuel from the burner 57.

Products of combustion from the combustion chamber 90 pass upwardly through a duct 74 having gas deflectors 75 attached to the outer surface thereof, so that as flue gas leaves the center of duct 74 and passes downward between the duct 74 and a liquid heating chamber 76, the deflectors 75 cause the gas to repeatedly scrub the wall of the liquid heating chamber, thus heating liquid therein. The flue gas then passes on downward between the cylin-

drical wall 72 and the pumping chambers 13 and 14 and is vented through a vent duct 77.

The apparatus of FIGURES 1, 3, 4, and 5 is shown in the same condition as the schematic diagrams of FIGURE 2. The vapor generated in chamber 11 has passed through the pumping chamber 13 and through the steam trap of duct 25, through the ports 65 of manifold 66 and is condensing in the condensing chamber 21. The ball 28 of the reversing ball valve 27 has moved to shut off duct 15, and ball 35 has raised off its seat to allow the inflow of return liquid from duct 34. The liquid which flows into the condensing chamber 21 is the coolest in the system, and after condensing the vapors it moves through an orifice 84 to a heating chamber 76 where it is heated by hot gases from duct 74 and deflectors 75. This heated liquid passes by a duct 78 to the bottom of the pumping chamber 13, and flows into the pumping chamber under the float 38 as the vapor therein condenses. Duct 78 of FIG. 1 corresponds generally to duct 23 of the schematic diagram of FIG. 2 except that heater 76 has been included in the duct circuit 78 of FIG. 1 and not in duct 23 of FIG. 2. For comparison purposes, the combination of duct 78 and heater 76 are numbered 23 in FIG. 1. Immediately upon moving of the ball 28 to the left side of the reversing valve 27, vapors generated in chamber 11 pass through duct 16 into the other pumping chamber 14 and force liquid, by depressing float 37 downward and out through valve 36 and into the inlet 81 of a turbine 82. The turbine is a metering type, or flood-ed, turbine, and discharges to the fluid outlet 32. The turbine 82 carries permanent magnets 83 which act upon the blower impeller 71 to drive it. Since this type of liquid turbine can deliver sufficient power, the blower may be geared up to the desired speed. An alternative construction may directly couple the turbine and blower, but requires liquid seals on the shaft which may be a source of leakage.

As the pumping cycle for chamber 14 is completed steam escapes through the trap of duct 26, manifold 62 and ports 63 into the condensing chamber 22, whereupon condensing it causes ball 28 to move to the right side of reversing valve 27 to start the next pumping cycle while, due to condensing in chamber 22, check valve 41 is closed and valve 42 opens to inflow of cool liquid which, after doing its share of condensing, passes through the restricted orifice 85, through a heating chamber 86 then through duct 87 to the bottom of the pumping chamber 14 where it replaces liquid just pumped out and stands ready for the next pumping cycle. Duct 87 of FIG. 1 corresponds generally to duct 24 of the schematic diagram of FIG. 2 except that heater 86 has been included in the duct circuit 87 of FIG. 1 and not in duct 24 of FIG. 2. For comparison purposes, the combination of duct 87 and heater 86 are numbered 24 in FIG. 1.

The pressure during the condensing cycles will depend upon the temperature of the returning liquid in duct 34, and the corresponding vapor pressure of the liquid, but during condensation this will ordinarily be subatmospheric. When the rapid condensing cycle is completed, the pressure in that portion of the system will rise. Thus parasitic steam generation is substantially eliminated, by promptly switching steam (or vapor) delivery from one pumping chamber to the other at the start of a condensing cycle.

We claim:

1. In a thermopump, in combination: a vaporizing chamber; conduit means for supplying a liquid to said vaporizing chamber to be vaporized therein; first and second pumping chambers; first and second condensing chambers; duct means including a reversing valve for delivering vapor from the vaporizing chamber alternatively to one and then to the other of said first and second pumping chambers; first and second U-shaped ducts connecting, respectively, said first pumping chamber to said first condensing chamber and said second pumping chamber.

ber to said second condensing chamber; first and second lower ducts connecting respectively the lower portion of said first pumping and condensing chambers and the lower portions of said second pumping and condensing chambers; inlet and outlet ducts connected to said first and second condensing chambers; a check valve in each said inlet and outlet duct; and means for supplying heat to liquid in said vaporizing chamber to vaporize liquid therein.

2. In a thermopump according to claim 1 said conduit means for adding a liquid to said vaporizing chamber comprises, first and second lower interconnecting ducts connecting said vaporizing chamber to said first and second pumping chambers; and check valves in each of said lower interconnecting ducts for preventing flow of liquid from said vaporizing chamber.

3. In a thermopump according to claim 1, duct means comprising a liquid expansion chamber interconnecting said inlets and said outlets.

4. Thermopump apparatus comprising, in combination: wall means forming a substantially vertical, annular vaporizing chamber with a central cylindrically shaped combustion chamber, a portion of said wall means defining a common cylindrical wall serving as the vertical wall of the combustion chamber and the inner vertical wall of the annular vaporizing chamber; a pumping chamber disposed concentrically about at least a portion of said vaporizing chamber, said vaporizing chamber and said pumping chamber being spaced radially from each other to form therebetween a gas passage for the flow of products of combustion therethrough; a vent connected to the bottom of said gas passage for venting products of combustion therefrom; wall means forming a heating chamber having an annular portion vertically aligned with said pumping chamber and secured thereabove and having a central cylindrical portion in fluid communication with said combustion chamber and said gas passage; closure means located at the top of said central cylindrical portion of the heating chamber to prevent the escape of flue gas from the top of the center of said heating chamber; a condensing chamber secured above said heating chamber; a burner arranged to release products of combustion in said combustion chamber to supply heat thereto and to direct the products of combustion into the central cylindrical portion of the heating chamber thereabove, said products of combustion passing from said central portion of said heating chamber, through said gas passage and out said vent; conduit means interconnecting said vaporizing chamber and said pumping chamber to supply vapor from said vaporizing chamber to said pumping chamber; conduit means for supplying a liquid to said vaporizing chamber to be vaporized therein; a U-shaped duct connecting said pumping chamber to said condensing chamber; an interconnection between said condensing chamber and the annular portion of said heating chamber; an interconnection between the annular portion of said heating chamber and said pumping chamber; inlet duct means comprising a check valve for supplying liquid to said condensing chamber; and an outlet duct means comprising a check valve in fluid communication with said condensing chamber for delivering liquid therefrom.

5. Thermopump apparatus comprising, in combination: wall means forming a substantially vertical, annular vaporizing chamber with a central cylindrically shaped combustion chamber, a portion of said wall means defining a common cylindrical wall serving as the vertical wall of the combustion chamber and the inner vertical wall of the annular vaporizing chamber; a pumping chamber disposed concentrically about at least a portion of said vaporizing chamber, said vaporizing chamber and said pumping chamber being spaced radially from each other to form therebetween an air supply chamber; a series of tubular ducts extending through said vaporizing chamber for supply air for combustion from said air supply chamber to said combustion chamber; means for supplying air

for combustion to said air supply chamber; wall means forming a heating chamber having an annular portion vertically aligned with said pumping chamber and secured thereabove and having a central cylindrical portion in fluid communication with said combustion chamber; a condensing chamber secured above said heating chamber; a burner arranged to release products of combustion in said combustion chamber to supply heat thereto and to direct the products of combustion into the central cylindrical portion of the heating chamber thereabove; conduit means interconnecting said vaporizing chamber and said pumping chamber to supply vapor from said vaporizing chamber to said pumping chamber; conduit means for supplying a liquid to said vaporizing chamber to be vaporized therein; a U-shaped duct connecting said pumping chamber to said condensing chamber; an interconnection between said condensing chamber and the annular portion of said heating chamber; a burner arranged to release products of combustion in said combustion chamber and secured above said heating chamber; a condensing chamber secured above said heating chamber; a burner arranged to release products of combustion in said combustion chamber to supply heat thereto and to direct the products of combustion into the central cylindrical portion of the heating chamber thereabove; conduit means interconnecting said vaporizing chamber and said pumping chamber to supply vapor from said vaporizing chamber to said pumping chamber; conduit means for supplying a liquid to said vaporizing chamber to be vaporized therein; a U-shaped duct connecting said pumping chamber to said condensing chamber; an interconnection between said condensing chamber and the annular portion of said heating chamber; a burner arranged to release products of combustion in said combustion chamber to supply heat thereto and to direct the products of combustion into the central cylindrical portion of the heating chamber thereabove; an air impeller for supplying air for combustion to said burner; a liquid turbine operatively connected to drive said air impeller; conduit means interconnecting said vaporizing chamber and said pumping chamber to supply vapor from said vaporizing chamber to said pumping chamber; conduit means for supplying a liquid to said vaporizing chamber to be vaporized therein; a U-shaped duct connecting said pumping chamber to said condensing chamber; an interconnection between said condensing chamber and the annular portion of said heating chamber; an interconnection between the annular portion of said heating chamber and said pumping chamber; inlet duct means comprising a check valve for supplying liquid to said condensing chamber; an outlet duct means comprising a check valve in fluid communication with said condensing chamber for delivering liquid therefrom; and duct means for passing liquid from said outlet duct means through said turbine.

6. Thermopump apparatus comprising, in combination: wall means forming a substantially vertical, annular vaporizing chamber with a central cylindrically shaped combustion chamber, a portion of said wall means defining a common cylindrical wall serving as the vertical wall of the combustion chamber and the inner vertical wall of the annular vaporizing chamber; a pumping chamber disposed concentrically about at least a portion of said vaporizing chamber; wall means forming a heating chamber having an annular portion vertically aligned with said pumping chamber and secured thereabove and having a central cylindrical portion in fluid communication with said combustion chamber, said heating and pumping chambers being fastened by separable joints; a condensing chamber secured above said heating chamber, said condensing and heating chambers being fastened by sepa-

rable joints; a burner arranged to release products of combustion in said combustion chamber to supply heat thereto and to direct the products of combustion into the central cylindrical portion of the heating chamber thereabove; conduit means interconnecting said vaporizing chamber and said pumping chamber to supply vapor from said vaporizing chamber to said pumping chamber; conduit means for supplying a liquid to said vaporizing chamber to be vaporized therein; a U-shaped duct connecting said pumping chamber to said condensing chamber; an interconnection between said condensing chamber and the annular portion of said heating chamber; an inter-connection between the annular portion of said heating chamber and said pumping chamber; inlet duct means comprising a check valve for supplying liquid to said condensing chamber; an outlet duct means comprising a check valve in fluid communication with said condensing chamber for delivering liquid therefrom.

8. Thermopump apparatus comprising, in combination: wall means forming a substantially vertical, annular vaporizing chamber with a central cylindrically shaped combustion chamber, a portion of said wall means defining a common cylindrical wall serving as the vertical wall of the combustion chamber and the inner vertical wall of the annular vaporizing chamber; an annular chamber disposed concentrically thereabout and divided by vertical walls therein into first and second pumping chambers; a chamber having an annular portion secured above said pumping chambers and divided by vertical walls therein into first and second heating chambers and having a central cylindrical portion in fluid communication with said combustion chamber; first and second condensing chambers secured above said heating chambers; means including a reversing valve for delivering vapor from the vaporizing chamber alternately to one and then to the other of said first and second pumping chambers; first and second U-shaped ducts connecting, respectively, said first pumping chamber to said first condensing chamber and said second pumping chamber to said second condensing chamber; first and second lower ducts connecting respectively the lower portion of said first pumping chamber to said first heating chamber and the lower portion of said second pumping chamber to said second heating chamber; first and second conduits connecting respectively said first heating chamber to said first condensing chamber and said second heating chamber to said second condensing chamber; inlet and outlet ducts in fluid communication with said first and second condensing chambers; a check valve in each said inlet and outlet duct; first and second interconnecting ducts connecting said vaporizing chamber to said first and second pumping chamber each having check valves for preventing flow of liquid from said vaporizing chamber; and a burner ar-

5 ranged to release products of combustion in said combustion chamber to supply heat thereto and to direct the products of combustion into the central cylindrical portion of said heating chambers thereabove.

9. Apparatus according to claim 4 and comprising a tubular duct extending upward from the top of said vaporizing chamber short of the top of said heating chamber whereby to direct flue gas upwardly through said duct then downwardly adjacent the inner wall of said annular heating chamber.

10. Apparatus according to claim 8 and comprising a circular wall spaced from and surrounding said vaporizing chamber to form between said vaporizing chamber and said pumping chamber an air supply chamber; a series of tubular ducts extending through said vaporizing chamber for supplying air for combustion to said combustion chamber; and means for supplying air to said air supply chamber.

11. Apparatus according to claim 8 and comprising an air impeller adapted to supply air for combustion to said combustion chamber; a liquid turbine operatively connected to drive said air impeller; and duct means for passing liquid from said outlet ducts through said turbine.

12. Apparatus according to claim 8 and comprising a pair of semi-circular insulating floats, one in each of said pumping chambers sized to substantially cover the surface of liquid therein, for reducing condensation of vapor in said pumping chambers.

13. Apparatus according to claim 8 wherein said means including a reversing valve includes a ball reversing valve having a central vapor inlet from said vaporizing chamber and opposing outlets, alternatively sealable by said ball, leading respectively to said first and second pumping chambers, said central vapor inlet being of less size than said opposing outlets whereby to accelerate movement of said ball during reversing of said ball.

14. Apparatus according to claim 8 and comprising a vapor distributing manifold in each of said condensing chambers, each connected to receive vapor from one of said U-shaped ducts and distribute said vapor in said condensing chambers.
